UNITED STATES PATENT OFFICE.

ROBERT FRIESE, OF CHARLOTTENBURG, GERMANY, ASSIGNOR TO SIEMENS-SCHUCKERTWERKE, G. M. B. H., OF BERLIN, GERMANY, A CORPORATION OF GERMANY.

REGULATING ELECTRIC-ARC LAMPS.

1,097,175.

Specification of Letters Patent.

Patented May 19, 1914.

Application filed July 15, 1913. Serial No. 779,154.

To all whom it may concern:

Be it known that I, ROBERT FRIESE, a subject of the German Emperor, and resident of Charlottenburg, near Berlin, Germany, have invented certain new and useful Improvements in Regulating Electric-Arc Lamps, of which the following is a specification.

My invention relates to a system of regulating electric arc lamps and has for its object more particularly to vary the intensity of light of such lamps especially for the purpose of stage illumination, which requires generally a regulation for decreasing the intensity of light of such lamps for 15 dimming, darkening or similar purposes. In systems of this kind which have heretofore been in use the regulating of arc lamps has either been done by inserting resistance in series therewith, and the dimming or 20 darkening more particularly has been accomplished by more or less shutting off the light of the lamps by means of shades, blinds, screens and similar mechanical auxiliaries. The former method of electrically 25 regulating arc lamps for dimming or darkening purposes apparently has the disadvantage of not being able to produce dimness of the light below a certain light intensity, as the arc lamp will not be able to 30 properly operate on a current below a certain limit, this limit being generally fixed by the hissing of the arc and by other factors depending upon the size and particular construction of the lamp, the electrodes 35 and so forth. On the other hand to produce the dimming or darkening effect solely by mechanical auxiliaries, such as shades, blinds, screens, and the like, results into the necessity of consuming the full operating 40 current during the entire dimming or darkening period, which is of course expensive and in some cases even prohibitive for commercial reasons.

In order to discard, therefore, the disadvantages of either mode of regulation and 45 to combine the advantages of both systems I have devised a new system of regulating arc lamps, which will enable one to install arc lamps for stage illumination purposes, 50 permitting a full regulation of the light between a maximum intensity and absolute darkness and especially a production of any degree of dimness within a minimum of current consumed.

My invention will be more fully understood by reference to the accompanying drawing which shows in a diagrammatic view the arrangement of an arc lamp with the regulating means according to my present invention.

Referring now more particularly to the drawing, I have shown an arc lamp 10, the arc of which is surrounded by a casing 11. This casing has an opening toward one side, and said opening is provided with a cover 12, which is hinged at the upper end of the opening as shown at 13. The arc lamp 10 is fed by the mains 14 and 15 over the switch 16 in such a way that, when said switch is thrown into a position as shown in the drawing, the full current will flow through the arc lamp, thus causing a maximum of light to be emitted therefrom. A regulating resistance 17 is connected with the switch 16 and may be inserted into the main 20 circuit of the lamp or cut out and into circuit in a number of steps as indicated by the contact points *a*, *b*, *c*, *d*, and *e*. Thus by moving switch 16 from contact *a*, over *b*, *c*, *d* to *e* the current flowing through the lamp will 25 be gradually weakened and produce a decrease of the light emitted therefrom. The regulating resistance 17 is so dimensioned relatively to the size and construction of the arc lamp, that if the full resistance 17 is 30 switched into circuit, the lamp will properly operate without trespassing the above mentioned limit, at which the current is no more sufficient to operate the arc in a proper manner. This limit I have found to lie, for 35 instance for a lamp of 15 amperes at a value of somewhat below 6 amperes, so that at 6 or 7 amperes the proper operation of the lamp at a decreased light emission will 40 yet be safeguarded. In order, now, to further decrease the light of the lamp beyond this limit, I make use of a mechanical auxiliary for gradually shutting off the opening of the lamp casing 11.

In the drawing I have shown an arrangement for closing the cover 12 electrically by a solenoid 18 with a plunger 19 which is connected over the cord 20 and the rollers 21 with the cover 12 in such a manner that the weight of the plunger 19 will tend to 45 keep the cover 12 in its uppermost position, while if the solenoid be excited the plunger 19 will be drawn into the solenoid 18 and

thereby gradually close the cover 12. For operating the solenoid 18 I connect the same between the main 14 and a regulable resistance 22 having a plurality of steps or contacts *f*, *g*, *h*, *i*, and *j* which may be operated in succession after the switch 16 has left the last contact *e* of the regulating resistance 17 in series with the arc. Also a contact segment 23 is connected with the last contact *e* of said regulating resistance 17 and so positioned that, while switch 16 is being moved from contact *e* over contacts *f*, *g*, *h* and *i* to *j*, the resistance 17 will always be kept in series with the arc during regulation of the resistance 22 for the solenoid 18. Thus by moving the switch 16 through the whole range from contact *a* to contact *j* the lamp will be regulated in steps between giving its maximum light and absolute darkness. During the first period of regulation, viz. between *a* and *e* the feeding current of the arc will be decreased down to a permissible value, and during the second period between *e* and *j*, the resistance 17 will further be kept in circuit with the arc over the contact segment 23 contacting with switch 16 and cause the lamp to operate at a minimum current, while at the same time the solenoid 18 will be excited by steps, thus gradually closing the cover 12 for the lamp.

In the foregoing I have shown and described only some embodiments of my invention, and I wish to be understood as not limiting myself to the exact constructions as shown and described, since changes may

be made thereon without departing from the principle of my invention.

I claim as new and desire to secure by Letters Patent of the United States:

1. In combination with an arc lamp, regulating means for reducing the operating current for said lamp, a device for shading said lamp and mechanism for causing said two means to operate in succession to each other. 40
2. In combination with an arc lamp, means for gradually reducing the operating current for said lamp down to a permissible amount, means for gradually shutting off the light emitted by said lamp, and switching instrumentalities for causing said two means to operate in succession to each other. 45
3. In combination with an arc lamp, a regulating resistance in series with the arc for regulating the current of said lamp, a dimming device for said lamp and mechanism for operating said regulating resistance and said dimming device in succession. 55
4. In combination with an arc lamp a regulating resistance in series with the arc, a dimming device for said lamp, a controller comprising steps for including said regulating resistance and subsequent steps for operating said dimming device. 60

In witness whereof I have hereunto set my signature in the presence of two subscribing witnesses.

ROBERT FRIESE.
